HEAT-TREATMENT OF METAL ARTICLES

Albert Edward Shorter, Sheffield, England, assignor to The Linde Air Products Company, a corporation of Ohio

Application April 9, 1943, Serial No. 482,367
In Great Britain June 3, 1942

8 Claims. (Cl. 266—4)

1

The present invention relates to the heat treatment of metal articles, and is concerned more especially with the surface hardening of localised surface portions, particularly those of circular shape such as the heads of bolts, tappet screws and firing pins; also annular surfaces such as ball races and small crown wheels.

For surface hardening articles having a limited superficial area there has been adopted a method known as "spot hardening." This method comprises applying high temperature heat to the surface to be treated so that the whole surface is raised to the required temperature, without effecting, during the heating period, any relative movement between the surface and the heating means. When the surface has attained the required temperature, the supply of heat is cut off, and the heated part is thereupon cooled or quenched.

In practice it has been found that a surface treated in this manner tends to crack on quenching. Such cracking is believed to be due, at least in part, to non-uniformity either in heating or in quenching or both, with consequent lack of uniformity in hardness as between different parts of the surface. Where an irregular surface is to be hardened, lack of uniform heating may be due to the difficulty of locating a suitable heating unit capable of raising all parts of the surface to a uniform temperature.

Again, when automatically hardening articles on a mass production basis where each of a series of similar articles is introduced in turn into a burner flame and then withdrawn therefrom, a localised portion of the leading edge of the surface and a similar localised portion of the trailing edge or even a narrow band extending across the surface may be subjected for a slightly longer period to the influence of the heating flame than the other parts of the surface, giving rise to non-uniformity in heating. For example, it has been proposed to insert bolts and like small articles in heat conducting blocks provided with pockets for the reception of the articles, and, while in these blocks, to feed the articles at selected intervals first to a heating device and then to a quenching device. It has been proposed to carry such a method into effect by means of apparatus comprising a rotatable drum over the periphery of which are distributed metal blocks having pockets for the reception of the articles to be hardened, and devices arranged above the upper half of the drum for feeding the articles to the pockets and for heating and chilling the exposed surfaces thereof. Owing to the presence of the heat con-

2

ducting blocks, it is possible in such cases to hold the articles for a sufficient time for the heat to be dispersed uniformly over the surface, but it has now been found that substantially uniform surface hardening can be achieved without the necessity of holding the articles in heat conducting blocks until the heat has spread uniformly over the surface if each article as it comes under the influence of the heating device is rotated about an axis passing through the surface to be hardened.

According to one feature of this invention therefore a method of heat treating a surface or a localised surface portion of a metal article 15 comprises directing high temperature heat thereupon simultaneously rotating the article about an axis normal or substantially normal to the surface or surface portion whereby the surface or surface portion is heated uniformly and cooling said heated surface.

According to another feature of this invention a method of heat treating a surface or surface portion of each of a series of articles comprises mounting the articles in spaced relationship, effecting a relative translatory movement between the articles and a source of high temperature heat in order to present each article in turn to the influence of the high temperature heat for a predetermined period and imparting to each 30 article while under the influence of the high temperature heat a rotary motion about an axis normal or substantially normal to the surface or surface portion to be heated.

Preferably, the rotary motion is imparted to 35 the article before the leading edge thereof comes under the influence of the high temperature heat whereby localised overheating of the leading edge is prevented. Likewise, it is preferred that, upon conclusion of the heating period, the 40 rotary motion of the article be continued until the trailing edge of the heated surface has moved out of the influence of the heat source whereby localised overheating of the trailing edge is prevented.

45 For the heat treatment of a circular surface of small diameter, such as a bolt head or valve tappet, a burner nozzle emitting a single or multiple jet may be used as the heat emitting source, but where more extended surfaces are to be heated a plurality of such burner nozzles may be required, being preferably so arranged that heat is distributed uniformly over the surface without overheating the edge portions which are then heated solely by conduction.

50 For heat treating an annular surface such as

a ball race, a multi-jet burner may be employed, the jets being spaced at intervals around the circumference of a circle having a diameter substantially equal to the mean diameter of the ball race so that the jets impinge centrally on the bottom of the ball groove. A series of quenching orifices may be disposed between the burner jets or in close proximity thereto so that the heating operation may, if desired, be followed by quenching. Where, as in the case of a crown wheel, the annular surface to be treated is of substantial width, a burner having a plurality of concentric rings of nozzles may be used and the spacing between the jets in one ring may differ from that in another ring to effect uniform heating of annular zones where the mass of metal in one zone differs from that in another zone. By spinning the annular surface, in accordance with the invention, whilst the surface is presented to the burner jets and quenching orifices, not only can uniform surface hardness be imparted to the surface but distortion is avoided.

To enable a series of similar articles to be heat treated on a mass production basis, the method aforesaid may be carried into effect by means of apparatus comprising a conveyor carrying a plurality of rotatable work supporting means each adapted to receive an article to be heat treated, the conveyor being movable intermittently so as to bring each work supporting means in succession to a feeding device adapted to feed an article to be heat treated to the supporting means and then to a heat treating device adapted to direct high temperature heat upon the surface to be heated, means being provided for rotating the supporting means whilst the article is under the influence of the applied heat. If it is desired to quench the heated surface, the heat treating device may comprise a heating unit and a quenching unit adapted to emit a stream of quenching fluid mounted in spaced relationship to the heating unit so that, as the conveyor advances from the feeding device, the article first comes under the influence of the heating unit and then upon further movement of the conveyor the heated surface is presented to the quenching fluid. Alternatively, a heat treating device comprising a heating and quenching unit combined to form a unitary structure may be employed, the conveyor in such case remaining stationary for a period of sufficient duration to enable both the heating and the quenching operations to be carried out at the same station. Depending upon the sharpness of the quench required, the quenching fluid may be a liquid such as cold water, oil or a mixture of soluble oil and water, or a gas, usually air.

By way of example an apparatus suitable for the repetition heat treatment of small parts on a mass production basis is shown in the accompanying drawings, in which—

Fig. 1 is a view of the apparatus in side elevation, some parts being shown merely diagrammatically and other parts, well known per se, being omitted for the sake of clarity;

Fig. 2 is a view of the same apparatus in front elevation;

Fig. 3 is a longitudinal section of a burner suitable for heat treating the tips of articles, such as firing pins;

Fig. 4 is a transverse section on the line IV—IV of Fig. 3; and

Fig. 5 is a longitudinal section of a burner suitable for heat treating annuli.

Referring to Figs. 1 and 2, the apparatus may

include, in general, a framework F on which are mounted a continuous conveyor in the form of a rotatable drum D carrying a plurality of rotatable work supporting means J, each adapted to hold an article A to be treated, a heat treating device comprising a heating unit H, a quenching unit Q, and a magazine M with automatic feeding means for loading the articles in turn on to the drum D. In operation, the articles to be heat treated are placed in the magazine M which feeds each in turn into the jigs J. Drum D is rotated intermittently in the direction of the arrow X so as to move the jigs carrying the articles from the loading station to the heating station. As the article is approaching the heating station, there is imparted to it in a manner described below, a rotary motion about an axis extending radially with respect to the drum D and normal to the surface to be heated, and this rotary movement continues until the article is moved out of the heating station. When the article is at the heating station, heating unit H heats the upper end surface thereof to the requisite temperature, the duration of the heating being determined empirically. From the heating station the article A is moved to the quenching station where the quenching unit Q cools the heated surface. When, upon further rotation of the drum D, the article A is conveyed to a station below the horizontal, it drops out of its jig and the latter, upon still further rotation of the drum D, returns to the loading position where it is loaded with another article from the magazine M.

The apparatus referred to in general terms above will now be described in further detail.

The drum D is mounted upon a horizontal shaft 10 supported in bearings carried by the framework F, the shaft being coupled to electrically energized driving mechanism 11 adapted to impart to the shaft an intermittent rotatory motion of variable frequency. The driving mechanism may, for example, comprise an electro-hydraulic reciprocating device or a variable delivery oil pump driven by a constant speed motor or a constant delivery pump having a by-pass valve and driven by a constant speed motor. The construction and arrangement of such driving mechanism are well known to those skilled in the art and only a diagrammatic representation thereof is accordingly given in the drawings.

The drum D is octagonal and carries eight jigs J, J₂, J₃, J₄, J₅, J₆, J₇, J₈. Jig J is mounted on a spindle 12 which extends radially from the drum D and is furnished with an annular boss or friction wheel 13 adapted, when at the heating station, to engage frictionally with a friction disc 14 mounted upon an horizontal shaft 15 which, like shaft 10, is journaled in bearings supported by the framework F, and is driven by a continuously rotatable electric motor 16. The other jigs are all identical with jig J.

The heating unit H comprises a burner held in a clamp 17 mounted on vertical and horizontal slides 18, 19, respectively, which permit of the burner nozzle being accurately located with respect to the surface to be treated. The burner is supplied with an oxy-fuel gas mixture through valves 20 having gas inlets 21, and a pilot light 22 may be provided to ignite the issuing gas jet.

The quenching unit Q is supplied with cold water from a reservoir 23, a pump 24 driven by an electric motor 25 serving to feed water from the reservoir 23 to the quenching unit Q. Water discharged by the quenching unit is led back to the reservoir by means of a shute 26 which also

serves to collect the treated articles as they drop out of the jigs.

The magazine M comprises a vertical housing 27 down which the articles are fed by gravity to a plunger 28 operable by means of a solenoid 29. When, in the course of rotation of the drum D, a jig comes into alignment with the plunger 28, the solenoid is energised causing the plunger 28 to thrust an article from the magazine into the jig.

The apparatus is adapted to be connected to the electric supply mains through conveniently located terminals and a master switch (not shown), and the supply of current to the driving mechanism 11, the friction disc motor 16, the pump motor 25 and the magazine solenoid 29 may be controlled by means of relays 30 housed in the lower part of the framework F. These relays are connected to double action push button switches 31, 32, 33, 34, 35, mounted upon a control panel 37. Switch 31 serves to start and stop the driving mechanism 11, switch 32 controls the friction disc motor 16, and switch 33 controls the pump motor 25. Switch 34 completes the circuit through the relay which controls the periodic energisation of the magazine solenoid 29, whilst switch 35 serves to set in motion the sequence of movements for carrying out the automatic heat treatment of a series of articles in the manner now to be described.

It will be assumed that the drum D is in the position shown in Fig. 2 where an article A in jig J is at the heating station and that the jigs J2 and J3 are each loaded with a similar article. Switches 31, 32, 33, 34 are placed in the "on" position and the gas valve 20 is turned on simultaneously with the closing of switch 35 to set the train of operations in motion. The periodic thrust imparted to the shaft 10 by the driving mechanism 11 will have previously been adjusted in frequency so that the drum D remains stationary for the requisite heating period, but immediately switch 35 has been closed friction disc 14 is set in motion to rotate the work as the heating flame impinges thereupon. At the conclusion of the heating period, an impulse is imparted by the driving mechanism 11 to shaft 10 so as to rotate drum D through one-eighth of a complete revolution. This brings jig J into the quenching position where water or other cold liquid from the quenching unit Q is directed upon the heated surface of article A whilst jig J2 is advanced to the heating station and as it does so, is caused to rotate by the friction disc 14 to spin the work in accordance with the invention. At the instant when drum D comes to rest with jig J2 at the heating station, the magazine solenoid 29 is momentarily energised through the intermediary of one of the relays 30 to feed an article from the magazine to the empty jig J4 which has advanced into alignment with plunger 28. After a period determined by the setting of the driving mechanism 11, drum D is again advanced through a distance of one-eighth of an arc of revolution to bring jig J2 into the quenching station. When, upon further advancement of the drum D, Jig J reaches the position occupied by jig J6 in Fig. 2, the article A falls out of its jig and drops into the chute 26. This series of operations continues automatically until switch 35 is opened.

When heat treating certain types of work it may be necessary for the quenching operation to be carried out immediately upon cessation of heating, that is to say, without introducing the delay which occurs in moving the article from the heat-

ing to the quenching stations in the manner described above. In such cases both operations may be carried out at one and the same station using a heat treating device comprising both heating and quenching means. Suitable heat treating devices for carrying such a method into effect are shown for instance in Figs. 3, 4 and 5 to which reference will now be made.

Figs. 3 and 4 show a device comprising twin burner nozzles 40 and triple quenching nozzles 41. Such a device may be used on plane surfaces but is especially useful for heat treating objects such as a firing pin 42, where the surface tapers to a point which is likely to become overheated if the flame from a single burner were to be directed thereon. By arranging the burner nozzles as shown in Fig. 3, so that the flames impinge not on the point but at zones removed a short distance therefrom, overheating of the point may be prevented.

The burner nozzles 40 and quenching nozzles 41 project from a block 43 provided with gas passages 44 and with passages 45 for the quenching medium. Gas passages 44 lead to a distributing chamber 46 adapted to be connected to the gas supply lines through the valves 20 (Figs. 1 and 2). Passages 45 connect to a header 47 supplied with quenching medium through pipe 48, the quenching medium also serving as coolant for the burner.

In the arrangement shown in Figs. 1 and 2, the burner may be perpetually alight and the quenching medium issuing continuously from the quenching unit but, where a heat treating device as shown in Figs. 3 and 4 is used, it is necessary to make provision for turning the gas supply on and off automatically at the commencement and conclusion respectively of each heating period, and for turning the supply of quenching medium on and off automatically at the commencement and conclusion respectively of each quenching period. For effecting the automatic control of the gas supply, valves 20 may be of the solenoid-operated type, the periods of operation being determined by means of gas timing mechanism 38 mounted on the panel 37. For controlling the quenching period, the quenching medium supplied by pump 24 may be arranged to pass through a solenoid operated valve 49 associated with quench timing mechanism 50 also mounted on panel 37. These valve-operated devices are arranged, through the intermediary of suitable relays, to be introduced into the cycle upon closure of a further push button switch 36 on panel 37.

Since both heating and quenching are to be effected at one and the same station, the frequency of the thrust imparted by the driving mechanism 11 to the shaft 10 must be adjusted to provide the requisite extended dwell at the heat treating station. This adjustment in frequency having been effected and the gas and quench-timing mechanism set at the appropriate values, the cycle of operations will be as follows.

With an article in the jig at the heat treating station and with switches 31, 32, 33, 34, 36 closed, the automatic push button switch 35 is closed. This causes, through certain of the relays 30, the energisation of the solenoids controlling the gas valves 20 to turn these valves on, and the gas is ignited by the pilot light 22. After a period determined by the setting of the gas timing mechanism 37, the gas supply is cut off and the supply of quenching medium is turned on by the automatic energisation of the solenoid-operated valve 49. Upon completion of the quenching period,

as determined by the setting of the quench timing mechanism 50, the supply of quenching medium is automatically cut off and the driving mechanism 11 rotates the drum D through one-eighth of a revolution to advance the next jig into the heat treating station. When this jig has attained this position, the gas supply is again automatically turned on whilst at the same time the magazine solenoid 29 is energised to cause plunger 28 to feed another article to the jig which has advanced into alignment therewith. This series of operations continues automatically until switch 35 is again opened.

For heat treating annuli such as ball races, a heat treating device comprising heating and quenching means as shown in Fig. 5 may be used. Like the device shown in Fig. 4, that shown in Fig. 5 comprises a plurality of burner nozzles 40 arranged uniformly around the circumference of a circle having a diameter substantially equal to the mean diameter of the annulus to be treated, quenching nozzles 41, burner block 43 with gas passages 44 and quench passages 45, gas distributing chamber 46 and header 47 for quenching medium supplied through pipe 48.

The device is mounted in position on the apparatus shown in Figs. 1 and 2 with the burner nozzles 40 located so as to direct the gas jets upon each annulus as the annulus is advanced in its jig to the heating station. To facilitate the location of the burner centrally with respect to the annulus, a central screw-threaded recess 51 accommodating a locating pin 52 may be provided in the burner block. The burner having been accurately located, the pin 52 is removed and the cycle of operations for effecting the desired heat treatment may then be carried out automatically as aforesaid.

Should it be desired to temper a surface hardened as aforesaid so as to impart greater toughness thereto, means may be provided for reheating the quenched surface to a temperature below the critical point. Where the heating and quenching are carried out at different stations, a reheating unit may be mounted in spaced relationship with respect to the quenching unit so that the quenched article comes under the influence of the reheating unit as the conveyor is advanced a further step. Alternatively, where the heating and quenching are carried out at one and the same station, the heating unit may be brought into operation to reheat the surface after it has been quenched, the duration of reheating being shorter than the initial period so as to ensure that the surface does not again attain the critical temperature. As in the case of the initial high temperature heating, the duration of reheating may be determined by means of timing mechanism adapted by means of a suitable relay to be brought into operation automatically upon cessation of the quenching operation.

In the foregoing particular description, the heat treatment has been described with reference to heating with gas burners, but it will be understood that electrical heating devices, such as electro-magnetic inductors, may be used in place of burners and that other modifications to the apparatus may be introduced without departing from the invention as set forth in the claims appendant hereto.

I claim:

1. For heat treating a surface or surface portion of each of a series of articles, apparatus comprising a heat treating device adapted to direct

high temperature heat upon the surface to be heated, a conveyor carrying a plurality of rotatable work supporting means, each adapted to receive an article to be heat treated, the conveyor being movable intermittently so as to bring each work supporting means in succession to a feeding device adapted to feed an article to be heat treated to the supporting means and then bring said supporting means with said article thereon to said heat treating device, in combination with means for rotating the supporting means whilst the article is under the influence of the applied heat.

2. Apparatus according to claim 1, wherein said heat treating device comprises a heating unit and a quenching unit adapted to emit a stream of quenching fluid mounted in spaced relationship to the heating unit so that as the conveyor advances from the feeding device, the article first comes under the influence of the heating unit and then, upon further movement of the conveyor, the heated surface is presented to the quenching fluid.

3. Apparatus according to claim 1 wherein said conveyor is coupled to driving mechanism adapted to impart an intermittent movement thereto, the frequency of the impulses imparted to the conveyor by said driving mechanism being variable in order that the duration of dwell may be adjusted to that required for carrying out the heat treatment.

4. Apparatus according to claim 1 wherein said heat treating device comprises a heating unit and quenching unit combined to form a unitary structure, the said conveyor being adapted to remain stationary for a period of sufficient duration to enable both the heating and quenching operations to be carried out at the same station.

5. Apparatus according to claim 1, wherein said heat treating device comprises a heating unit and quenching unit combined to form a unitary structure, the said conveyor being adapted to remain stationary for a period of sufficient duration to enable both the heating and quenching operations to be carried out at the same station, and wherein the duration of the heating operation and that of the quenching operation are determined automatically by timing mechanisms.

6. Apparatus according to claim 1, wherein said heat treating unit and a quenching unit adapted to discharge a stream of quenching fluid mounted in spaced relationship to the heating unit so that as the conveyor advances from the heating device, the article first comes under the influence of the heating unit and then, upon further movement of the conveyor, the heated surface is presented to the quenching fluid, and wherein means are provided for reheating the quenched surface so as to impart greater toughness thereto.

7. A heat treating apparatus for small articles comprising a drum rotatable about an axis and having a plurality of rotatable article-supporting means, each of said article-supporting means including a rotary element, a heat treating device and a rotating device respectively radially spaced from the drum axis, said rotating device being adapted to be successively engaged by the rotary elements of the respective article-supporting means prior to a leading edge of the article coming under the influence of the heating unit and continuing in engagement therewith until a trailing edge is out of the influence of the heating unit.

8. Apparatus as claimed in claim 7, in which the radial spacing of the heat treating device is

greater, and that of the rotating device is less, than that of the article supporting means.
